ABRADING MACHINE KNEE

Loren E. Thompson, Parkersburg, W. Va.

Application September 16, 1943, Serial No. 502,668

10 Claims. (Cl. 51—233)

This invention relates to abrading machines, and is a continuation-in-part of my copending application Ser. No. 478,925, filed March 12, 1943 for Abrading apparatus.

An object of this invention is to provide an improved knee or work carrier support which is vertically adjustable on a base structure, the knee embodying self-contained means for raising or lowering the knee relative to the base structure.

Another object of this invention is to provide in combination with a base structure including an upstanding standard, a knee which is vertically slidable on the standard, and an improved hydraulic locking means for locking the knee in adjusted position.

A further object of this invention is to provide in an abrading machine a knee or work carrier support and hydraulic means for adjusting the position of the knee relative to a base structure.

A further object of this invention is to provide in combination with a vertical standard carried by a base member, a vertically adjustable knee, a locking wedge for holding the knee in adjusted position, and a hydraulic operator for the locking wedge.

A further object of this invention is to provide in a work carrier support an improved adjusting means therefor which will eliminate inaccuracies of adjustment due to wear of parts which occur in screw adjusting mechanisms.

The invention consists of the novel construction, combination and arrangement of parts as will be more specifically referred to and illustrated in the accompanying drawings wherein is shown an embodiment of the invention, but it is to be understood that changes, modifications and variations may be resorted to which fall within the scope of the invention as claimed.

In the drawings:

Figure 1 is a detail front elevation of an abrading machine partly broken away and in section embodying this invention.

Figure 2 is a detail end elevation of the machine.

Figure 3 is a fragmentary horizontal section taken on the line 3—3 of Figure 1.

Figure 4 is a sectional view taken on the line 4—4 of Figure 3.

Figure 5 is a fragmentary sectional view taken on the line 5—5 of Figure 3, and

Figure 6 is a fragmentary sectional view taken on the line 6—6 of Figure 5.

Referring to the drawings, the numeral 10 designates generally a base having an upright or standard 11 extending therefrom on which an

improved knee structure 12 constructed according to an embodiment of this invention is slidably mounted.

The knee structure 12 is of hollow construction, as will be hereinafter described, and has mounted on the upper portion thereof a saddle 13 carrying a cradle 14 and a slidable work supporting member 15 is carried by the cradle 14. The standard 11 has mounted on the upper end thereof of a motor 16 having a pair of abrading wheels 17 and 18 secured to the armature shaft thereof with the abrading wheels confronting the longitudinal inner edges of the two work supporting members or carriages 15 which are mounted on the pair of knees 12 slidably carried by the opposite vertical sides of the standard 11.

The two knees 12 are of like construction and the detailed description of one of these knees will apply equally as well to the other knee. The knee 12 comprises a front wall 19, opposite end walls 20, a rear wall 21, a top wall 22 and a bottom wall 23. A rearwardly projecting slide structure 24 extends rearwardly from the rear wall 21 and includes a pair of V-shaped slide members 25 which slidably engage in a truncated V-shaped guide 26 which is formed integral with one side of the standard 11.

The knee 12 is adapted to be raised by hydraulic means including a pump 27 which is operated from a motor 28. The interior of the knee 12 includes a pair of inner walls 29 and 30 extending rearwardly from the front wall 19 and connected at their rear ends to an inner wall 31 parallel with the front wall 19. The walls 29, 30 and 31 define with the central portion of the front wall 19 a central chamber 32. An inner bottom wall 33 is disposed between the side walls 29—30 and the front wall 19 and rear wall 31, forming a liquid reservoir 34 below the chamber 32. The pump 27 is connected by means of an intake pipe 35 to a strainer 36 disposed in the reservoir 34. The knee 12 has fixedly disposed therein a pair of vertically disposed cylinders 37, one cylinder 37 being disposed between the side wall 29 and the adjacent end wall 20, whereas the other cylinder (not shown) is disposed between the side wall 30 and the other end wall 20.

The cylinder 30 is in the present instance secured to a connecting web 38 formed integral with the rear wall 21 and the cylinder 37 opens through the bottom wall 23 and is connected at its upper end to an upwardly offset wall 38. The wall 38 is formed with a guide channel 39 of truncated V-shaped configuration for slidably supporting the saddle 13. The bottom wall 23 is

formed with a recess 40 about the lower open end of the cylinder 37 and a plate 41 is secured in the recess 40 by fastening members 42. A top plate or head 43 is mounted in a recess 44 formed in the upper end of the cylinder 37 so as to maintain the upper end of the cylinder closed.

A stationary piston 45 slidably engages through the lower plate 41 and is adapted at its lower end to rest on the upper side of the base 10. The cylinder 37 is formed with a fluid passage 46 opening into the upper end of the cylinder and the top wall 22 is also formed with a fluid passage 47 communicating at one end with the passage 46. A fluid conducting pipe 48 is connected at one end to the opposite end of the fluid passage 47 and is connected at the opposite end thereof to a three-way valve 49. The valve 49 has connected thereto an intake pipe 50 which is connected to a pressure relieving valve structure 51. The pressure relieving structure 51 is of conventional construction and is connected by means of a pipe 52 to the outlet or pressure side of the pump 27. The pressure relieving valve structure 51 has connected thereto a discharge pipe 53 which is also connected with the inner bottom wall 33 and discharges into the reservoir 34. The valve 49 has connected thereto a return pipe 54 which is connected to a vertically disposed return or discharge pipe 55.

The discharge pipe 55 communicates with the reservoir 33 so that when the valve 49 is shut off with the knee 12 in the desired raised position, the pump 27 may continue in operation with the fluid flowing from the pipe 50 through the valve 49 back through the return pipes 54 and 55 to the reservoir 33. A second pressure pipe 56 is connected at one end to a T 57 which is interposed in the pipe 48 and the pipe 56 is connected to an oppositely disposed fluid conducting channel 47a which communicates with the opposite cylinder 37 (not shown).

In order to provide a means whereby the knee 12 may be locked in its adjusted position along the length of the standard 11, I have provided a pair of knee locking members, generally designated as 58. The locking members 58 each include a substantially triangular locking member or wedge 59 which is secured to an elongated stem 60. The stem 60 is slidable in a guide 61 disposed between the wall 31 and the slide 26. The angled edge 62 of the locking member 59 is adapted to bear against the adjacent angled edge or face of the truncated V-shaped guide 26. The stems 60 are slidable through the guide members 61 and are connected together at their forward ends by means of a connecting bar 63. Preferably, a nut 64 is threaded onto each stem 60 and is adapted to bear against a boss 65 carried by the inner wall 31 within the chamber 32.

A pair of inwardly projecting guides 66 are carried by the wall 29 and slidably support the forward ends of the stems 60. The two locking members 58 are adapted to be moved to a knee locking position by means of a hydraulic operator generally designated as 67. The operator 67 includes a cylinder 68 provided with a bar 69 which is secured by fastening members 70 to the inner side of the wall 29. A piston 71 is slidable in the cylinder 68 and has secured thereto one end of a piston rod 72. The opposite end of the piston rod 72 is secured in any suitable manner to the central portion of the connecting bar or crosshead 63. If desired, a spring 73 may be disposed about the piston rod 72, bearing at one end against the adjacent end of the cylinder 68

and at the opposite end against the connecting bar or crosshead 63.

The cylinder 68 has connected to the inner portion thereof one end of a pressure conducting pipe 74. The other end of the pipe 74 is connected to a valve 75. The valve 75 is preferably a three-way valve which is connected by means of a pipe or nipple 76 to the pipe 50. A return fluid conducting pipe 77 is connected at one end to the valve 75 and at the other end to a T 78 which connects the pipes 54 and 55 together. In this manner the return fluid from the cylinder 68 is adapted to return through the pipe 74, the valve 75 and the nipple or pipe 77 to the return pipe 55.

The rear portion of the knee 12 is formed with a downwardly tapered fluid guide 79 which is open at its upper end, being formed with a concave upper open end portion 80 and a lower open end 81 for discharging cutting fluid from the abrading wheels onto the upper surface of the base 10. The base 10 is of hollow construction and the cutting fluid within the base 10 is withdrawn by means of a pump 82 which is connected at its suction side by means of a pipe 83 to an intake strainer 84. The outlet side of the pump 82 is connected by means of a pipe 85 to a pair of upwardly extending pipes 86 which are adapted to be connected to fluid discharging nozzles 87 which are connected to the pipes 86 by a flexible hose 88, as shown in Figure 2.

The fluid supply line 50 has connected thereto a pipe line 89 and preferably a four-way valve 90 is interposed in the pipe 89, the valve 90 being connected by means of a pipe 91 to the return pipe 54. The fluid pressure line 89 has connected to the outer end thereof a flexible pipe or hose 92 which is connected to a head 93 carried by the cradle 14. The four-way valve 90 is of conventional construction and is adapted in one position thereof to communicate fluid pressure from the pipe 53 to the pipe 89 and in another position thereof to communicate the pipe 89 with the return pipe 91, cutting off the pressure supply pipe line 50.

The front wall 19 of the knee 12 is formed with a plurality of horizontally disposed keyways or slots 94, the slots 94 being of T-shaped configuration for receiving headed bolts or the like to fasten work or other articles on the front side of the wall 19.

In the use and operation of this structure, when it is desired to raise the knee 12 the valve 49 is opened to communicate the pressure supply line 50 with the ducts 47 and 47a. The fluid pressure will then enter the cylinder 37 and raise the knee 12 to the desired position. When the knee 12 is in its desired vertical position, the valve 49 may be cut off and the valve 75 may then be opened to communicate the hydraulic locking member 67 with the pressure line 50. The fluid pressure entering the cylinder 68 on the rear side of the piston 71 will move the piston 71 to the left, as viewed in Figure 5 thereby pulling the locking members 58 forwardly to a locked position. The valve 75 may then be closed without communicating the pipe 74 with the return pipe 55. The knee will then be locked in its vertically adjusted position.

With a hydraulic operator for raising the knee as hereinbefore described, there will be no lost motion due to wear of the elevating structure as is the case where gears or threaded shafts are used to raise and lower the knee. The knee forms a part of a work support or carriage

embodied in my copending application Serial Number 478,925 supra. After the knee 12 has been raised to the desired position and locked in this position, the motor 28 may be cut off so that the pump 27 will not continue in operation and any excess pressure returned through the pressure relieving valve structure 58 to the fluid reservoir 34.

When it is desired to lower the knee, the valve 15 may be adjusted to communicate the pipe 74 with the return pipe 55. The spring 13 will move the locking members 53 to a released position, whereupon the valve 49 may be moved to a position communicating the pipes 48 with the return pipe 54. The knee being relatively heavy will gravitantly move downwardly to the desired position.

This knee structure has been constructed as part of a relatively heavy grinding machine and by having the elevating structure for the knee actuated by hydraulic means, the abrading machine can be made more compact and at a lower cost than where the elevating or adjusting structure is formed of gears or threaded shafts. In addition by actuating the knee through a hydraulic means, the adjustment for the knee can be made to a more finer degree than has heretofore been possible with mechanically operated adjusting means.

What I claim is:

1. In an abrading machine, a base, a standard rising from said base, a work supporting knee vertically slidable on said standard, hydraulic means carried by and disposed within said knee for raising said knee, and means carried by said knee engageable with said standard for locking said knee in vertically adjusted position.

2. In an abrading machine, a base, a standard rising from said base, a work supporting knee vertically slidable on said standard, hydraulic means carried by and disposed within said knee for raising said knee, and hydraulically operated means carried by said knee engageable with said standard for locking said knee in vertically adjusted position.

3. In an abrading machine, a base, a standard rising from said base, an elongated horizontally disposed work support vertically slidable on said standard, a pair of vertically disposed cylinders fixed relative to said support, stationary pistons slidable in said cylinders and engaging said base at their lower ends, and fluid pressure means connected to said cylinders for vertically raising said support.

4. In an abrading machine, a base, a standard rising from said base, an elongated horizontally disposed work support vertically slidable on said standard, a pair of vertically disposed cylinders fixed relative to said support, stationary pistons slidable in said cylinders and engaging said base at their lower ends, and fluid pressure means connected to said cylinders for vertically raising said support, said pressure means being contained within said support.

5. In an abrading machine, a base, a standard rising from said base, an elongated horizontally disposed work support vertically slidable on said standard, a pair of vertically disposed cylinders fixed relative to said support, stationary pistons slidable in said cylinders and engaging said base

at their lower ends, fluid pressure means connected to said cylinders for vertically raising said support, wedge-shaped locking means carried by said support engageable with said standard for locking said support in adjusted position, and operating means for said locking means.

6. In an abrading machine, a base, a standard rising from said base, an elongated horizontally disposed work support vertically slidable on said standard, a pair of vertically disposed cylinders fixed relative to said support, stationary pistons slidable in said cylinders and engaging said base at their lower ends, fluid pressure means connected to said cylinders for vertically raising said support, wedge-shaped locking means carried by said support engageable with said standard for locking said support in adjusted position, and a fluid pressure operator for said locking means.

7. In an abrading machine, a base, a standard rising from said base, an elongated horizontally disposed work support vertically slidable on said standard, a pair of vertically disposed cylinders fixed relative to said support, stationary pistons slidable in said cylinders and engaging said base at their lower ends, fluid pressure means connected to said cylinders for vertically raising said support, wedge-shaped locking means carried by said support engageable with said standard for locking said support in adjusted position, and a fluid pressure operator for said locking means, said operator also connected to said fluid pressure means.

8. In an abrading machine, a base, a standard rising from said base, guide means carried by said standard, a hollow work supporting knee slidably engaging said guide means, means dividing said knee into a central chamber and a pair of outer chambers, a vertical cylinder in each outer chamber, a pair of upright pistons extending upwardly from said base and slidable in said cylinders, and hydraulic means in said central chamber connected to said cylinders for vertically adjusting said knee.

9. In an abrading machine, a base, a standard rising from said base, guide means carried by said standard, a hollow work supporting knee slidably engaging said guide means, means dividing said knee into a central chamber and a pair of outer chambers, a vertical cylinder in each outer chamber, a pair of upright pistons extending upwardly from said base and slidable in said cylinders, hydraulic means in said central chamber connected to said cylinders for vertically adjusting said knee, and means for locking said knee in adjusted position.

10. In an abrading machine, a base, a standard rising from said base, guide means carried by said standard, a hollow work supporting knee slidably engaging said guide means, means dividing said knee into a central chamber and a pair of outer chambers, a vertical cylinder in each outer chamber, a pair of upright pistons extending upwardly from said base and slidable in said cylinders, hydraulic means in said central chamber connected to said cylinders for vertically adjusting said knee, and hydraulic means in said central chamber for locking said knee in adjusted position.

70 LOREN E. THOMPSON.
